UNITED STATES PATENT OFFICE.

ALFREDO BOWEN, OF SANTIAGO, CHILE.

AUTOMATIC TROLLEY RETRIEVER FOR ELECTRIC TRAMCARS.

Application filed May 18, 1922. Serial No. 561,945.

To all whom it may concern:

Be it known that I, ALFREDO BOWEN, a citizen of the Republic of Chile, residing at Santiago, Republic of Chile, have invented 5 Improvements in Automatic Trolley Retrievers for Electric Tramcars, of which the following is a specification.

This invention relates to automatic electric tramcar trolley retrievers of the type in which a normally supported weight is released by the upward jerk on the trolley cord when the trolley leaves the cable and then overcomes the action of the trolley springs and draws down the trolley pole 15 thus obviating damage to the overhead gear.

According to the present invention the retriever comprises a body or weight mounted to slide up and down on a bar or other suitable guide, a drum carried by the body 20 and having wound on it the trolley cord, a spring tending to rotate the drum so as to wind up said cord a catch normally engaging the body with the upper part of the guide and means carried by the drum and 25 adapted, when the latter is quickly rotated by the unwinding of the cord, to be thrown outwards by centrifugal force and to disengage the catch from the guide, the catch then preventing further rotation of the 30 drum so that the body or weight sliding downwards along the guide draws down the trolley.

Such a retriever may be constructed in various ways.

35 Referring to the accompanying drawings:

Figs. 1 and 2 are respectively side and end elevations to a small scale of a retriever fitted to a tramcar.

Fig. 3 is a plan of the retriever;

40 Fig. 4 an elevation with parts broken away;

Fig. 5 a section on the line A A Fig. 4;

Fig. 6 a section on the line B B Fig. 5;

45 Fig. 7 is a detail sectional plan of a guide bar supporting bracket.

In this construction, the body or weight is in the form of a box 10 with a removable front cover 11, the cavity being circular as to its lower part but extended in an upward 50 direction, as seen clearly in Fig. 6; the drum 12 is mounted on a stud 13 projecting from the back of the box 10 and coaxial with the circular part of the cavity. A coiled spring 14 contained in the drum 12 connects it to the stud 13, and the trolley cord 15 is led 55 through a hole in the top of the box and

wound on the drum, the arrangement being such that the spring 14 maintains the trolley cord in tension whilst permitting rise and fall of the trolley pole, due to variations in the height of the trolley cable so long as the box is held at the upper part of guide bar 18 by a spring catch 16, which is pivoted in the upper part of the box 10, engaging a groove or recess 17 in the side of 60 the guide bar 18 mounted at the end of the tramcar. The box 10 is formed with clasps or eyes through which the guide bar extends and the guide bar 18 is fixed to the ends of brackets 19 attached to the mud 65 guards of the car; to enable the retriever to be moved from one end of the car to the other, the brackets 19 are formed with button ends 19^a (see Fig. 7) and the guide bar with corresponding button hole slots 18^a, 70 75 movement of the bar being prevented by a spring catch 20 carried by one of the brackets overlapping the end of the bar. Through the catch 20 is screwed a pin 21 which can be caused to enter holes in the 80 bracket to hold the catch in its operative or inoperative position. The drum is formed at its inner end with a disc 22 having say three projections 23 on its rear face which are bored radially to receive freely 85 movable plungers 24; above the plungers is pivoted the catch 16 which projects through an opening in the back of the box, a helical spring 25 around its pivot pressing it against the guide bar 18. The head of each 90 95 plunger is formed with a projecting flange 24^a. 26 is a lifting cord attached to the box 10.

When the tramcar is in movement, the retriever should be placed on the higher 95 part of the guide bar 18 and held in this position by the catch 16 fitting into the groove or recess 17 on the guide bar. When, for any reason, the trolley wheel 27 (Figs. 1 and 2) leaves the cable, the cord 15 is 100 jerked violently upwards, causing the drum 12 to revolve at a high velocity and consequently, owing to centrifugal force, the plungers 24 try to move outwards but are restrained so long as they are opposed to 105 the circular wall of the box but when they arrive at the upper eccentric hollow, they move upwards and strike against the catch 16. The catch is consequently pushed sideways and comes out of the groove or recess 110 17 in the guide bar and, as there remains nothing to hold the retriever in its original

stable position, it descends along the guide bar, pulling down with it the trolley pole 28 by means of the cord. The plunger 5 striking the catch engages with it and is prevented from falling back into its normal position by its projecting flange 24^a and thus stops the action of the drum during the time the retriever is operating by its own weight. If the cord 15 is eased by pulling it downwards with the hand, the compensation spring 14 causes the drum to revolve in the opposite direction, releasing the plunger 24, which returns to its resting position. In order to return the retriever to its original position, the conductor will pull the cord 26 with one hand, holding the cord 15 of the trolley pole with the other and, on arriving at the groove or recess 17 in the guide bar, the catch 16 will automatically 20 engage therein. The conductor will then proceed to place the trolley wheel on the cable.

What I claim is:—

1. An automatic trolley retriever for an electric tramcar comprising a body, a guide on which said body slides, a drum carried by the body and having wound on it the trolley cord, a spring tending to rotate the drum so as to wind up said cord, a catch 25 normally engaging the body with the upper part of the guide and means carried by the drum and adapted, when the latter is quickly rotated by the unwinding of the cord, to be thrown outwards by centrifugal force and to engage the catch, thus disengaging it from the guide, preventing rotation of the drum and releasing the body, substantially as described.

2. An automatic trolley retriever for an electric tramcar comprising a box-like body having a cavity circular at its lower part, a fixed stud coaxial with said circular part, a trolley cord winding drum mounted on said stud, a coiled spring connecting said drum 40 to said stud, a catch normally engaging the body with the upper part of the guide and means carried by the drum and adapted, when the latter is quickly rotated by the unwinding of the cord, to be thrown outwards by centrifugal force and to engage the catch,

thus disengaging it from the guide, preventing rotation of the drum and releasing the body, substantially as described.

3. An automatic trolley retriever for an electric tramcar comprising a body, a guide 55 on which said body slides, a drum carried by the body and having wound on it the trolley cord, a spring tending to rotate the drum so as to wind up said cord, a catch normally engaging the body with the upper part of the guide and radially arranged plungers carried by the drum and adapted, when the latter is quickly rotated by the unwinding of the cord, to be thrown outwards by centrifugal force and to engage the catch, 60 thus disengaging it from the guide, preventing rotation of the drum and releasing the body, substantially as described.

4. An automatic trolley retriever for an electric tramcar comprising a box-like body 70 having a cavity circular at its lower part, a fixed stud coaxial with said circular part, a trolley cord winding drum mounted on said stud, a coiled spring connecting said drum to said stud, a spring catch pivoted 75 within the upper part of said cavity and extending to the exterior thereof and adapted to engage the box-like body with the upper part of the guide, radially arranged plungers carried by the drum and adapted, 80 when the latter is quickly rotated by the unwinding of the cord, to be thrown outwards by centrifugal force and to engage the catch, thus disengaging it from the guide, preventing rotation of the drum and 85 releasing the body, substantially as described.

5. In an automatic electric tramcar trolley retriever of the type referred to, a normally supported weight formed with 90 eyes, a guide bar extending through the eyes and formed with button hole slots, button-ended brackets attached to the car, and adapted to engage in said slots, and a catch adapted to engage the guide bar and 95 brackets, substantially as described.

Signed at American Embassy, Santiago, Chile, South America, this 7th day of February, 1922.

ALFREDO BOWEN.
